UNITED STATES PATENT OFFICE.

ROBERT J. MORRISON, OF WAYNE, PENNSYLVANIA.

BRAD FEEDING AND DRIVING APPARATUS.

1,024,645.

Specification of Letters Patent.

Patented Apr. 30, 1912.

Application filed July 28, 1911. Serial No. 641,057.

To all whom it may concern:

Be it known that I, ROBERT J. MORRISON, a citizen of the United States, residing at Wayne, in the county of Delaware and State 5 of Pennsylvania, have invented certain new and useful Improvements in Brad Feeding and Driving Apparatus, of which the following is a specification.

My invention relates to improvements in 10 brad feeding and driving apparatus, the object of the invention being to provide a hand operated device which will feed and drive brads at every operation of the device.

While the device is especially adapted for 15 use in driving brads into cork tile, it is not limited to this use, but may be adapted for any work where brads or nails of small size are used such as can be driven by the depression of a hand operated plunger.

With these and other objects in view, the 20 invention consists in certain novel features of construction and combinations and arrangements of parts, as will be more fully hereinafter described and pointed out in the 25 claims.

In the accompanying drawings: Figure 1, is a view in side elevation illustrating my invention with the parts in normal position. Fig. 2, is a view in longitudinal section of Fig. 1. Fig. 3, is a view partly in longitudinal section and partly in elevation illustrating the device in its driven position. Fig. 4, is a view in section on the line 4—4 30 of Fig. 3. Fig. 5, is a view in section on the line 5—5 of Fig. 3, and Fig. 6, is a fragmentary view in side elevation at right angles to Fig. 3.

In constructing my improved device, I 40 employ a cylindrical plunger 1 having a central longitudinal passage 2 through which brads 3 are downwardly fed. The upper end of this plunger is preferably made integral with a handle 4 into which the conical lower end of a reservoir 5 is secured by means of 45 a screw 6. This reservoir is adapted to contain a quantity of brads, and feed them one at a time down the passage 2.

The upper end of the reservoir is normally 50 closed by a removable plug 7, so that it can be refilled whenever desired. The lower portion of the plunger is of two external diameters, forming an annular shoulder 8, adjacent handle 4, and around the larger

diameter of this plunger is a cylindrical shell 9, which is secured to the plunger by 55 means of a pin or rivet 10.

Between the shell and the smaller diameter of the plunger, a cylindrical barrel 11 is located, and a coiled spring 12 is positioned around the small diameter of plunger 60 1, between the upper end of barrel 11 and the shoulder 8, and exerts downward pressure on the barrel to normally hold the same in the position shown in Figs. 1 and 2.

The lower end of the barrel 11 is closed 65 by a plate 13 having a central opening through which the brads 2 are discharged. Around this discharge opening, elastic strips are bent forming a spring mouth 14 to exert friction against the brads as they 70 are moved through the opening, and a cushion 15 preferably of leather, or other suitable material, is secured to the lower end of the barrel by screws 16, or in any other approved manner, so as to cushion the blow 75 when a brad is driven.

A clamping collar 17 is secured around the shell 9, near its upper end, by means of bolts 18 and nuts 19, and the outwardly projecting members of said collar constitute parallel 80 bars 20, between which, and on one of said bolts 18, the upper end of a lever 21 is pivoted. The lower end of this lever 21 is bifurcated to straddle a bar 23, and these bifurcated portions are made with longitudinal slots 22 to receive lugs 24 on the bar 23. Bar 23 moves through an opening 25 in shell 9, through a slot 26 in the barrel 11, and into a transverse opening 27 in plunger 1. Opening 27 extends across the passage 2, 90 and the inner end of the bar 23 is beveled as shown at 28, so as to readily force itself between the beveled ends of the adjacent brads.

A wedge block 29 is secured to barrel 11 95 by means of screws 30, and is grooved at its outer inclined edge to receive and bear against lever 21. This lever 21 is held against the wedge by means of a bow spring 31 secured by screws 32 to the shell 9. 100

Figs. 1 and 2 show the parts in normal set position. When the handle is forced downwardly, the plunger 1 and shell 9 move downwardly, while the barrel 11 is held against the tile or other article into which 105 the brad is to be driven. As the barrel

moves downwardly, lever 21 is carried downwardly, and as its relation with the wedge 29 changes, spring 31 forces bar 23 inwardly across passage 2. This bar 23 then acts as a fixed head, limiting the upward movement of the lowest brad, so that a continued downward movement of the plunger serves to drive this brad into the tile or other article. When the pressure on the handle is released, 10 spring 12 returns the parts to their normal position, and the device is ready for a similar operation. It will therefore be noted that it is simply necessary to grasp the handle 4, and force the latter downwardly to 15 drive a brad, and this operation may therefore be rapidly accomplished, and the device result in a great saving of time and labor.

Various slight changes might be made in the general form and arrangement of parts 20 described without departing from my invention, and hence I do not limit myself to the precise details set forth, but consider myself at liberty to make such changes and alterations as fairly fall within the spirit 25 and scope of the appended claims.

Having thus described my invention, what I claim as new and desire to secure by Letters Patent is:

1. A device of the character described, 30 comprising a plunger having a brad passage therethrough, a shell around the plunger and spaced therefrom, a barrel located between the shell and the plunger, a spring around the plunger exerting downward pressure on the barrel, a bar movable across the passage in the plunger, a spring pressed lever engaging said bar, said shell having a slot therethrough, and a block secured to the barrel, and engaging the lever, 35 said block having an inclined outer edge, substantially as described.

2. A device of the character described, 40 comprising a plunger having a brad passage therethrough, a shell around the plunger and spaced therefrom, a barrel located between the shell and the plunger, a spring around the plunger exerting downward pressure on the barrel, a bar movable across the passage in the plunger, a spring pressed 45 lever engaging said bar, said shell having a slot therethrough, a block secured to the barrel, and engaging the lever, said block having an inclined outer edge, a pivotal support for said lever consisting of a collar 50 clamped around the shell, bolts clamping said collar, and one of said bolts constituting a pivot for said lever, substantially as described.

3. A device of the character described, 55 comprising a hollow plunger constituting a passage for brads, a shell secured around the plunger and spaced therefrom, said shell having a slot therein, a barrel located between the shell and the plunger, a spring 60 exerting downward pressure on the barrel,

a pivoted lever, a bar, said shell and plunger having openings for the reception of the bar, said barrel having a slot for the reception of said bar, said lever connected at its free end to said bar, a spring exerting 70 inward pressure on the lever, and a wedge block fixed to the barrel and projecting through the slot in the shell and engaging said lever, substantially as described.

4. A device of the character described, 75 comprising a hollow plunger constituting a passage for brads, a shell secured around the plunger and spaced therefrom, said shell having a slot therein, a barrel located between the shell and the plunger, a spring 80 exerting downward pressure on the barrel, a pivoted lever, a bar, said shell and plunger having openings for the reception of the bar, said barrel having a slot for the reception of said bar, said lever connected at 85 its free end to said bar, a spring exerting inward pressure on the lever, a wedge block fixed to the barrel and projecting through the slot in the shell and engaging said lever, a handle on the upper end of said plunger, 90 and a reservoir secured in said handle and constructed to direct brads into the passage of said plunger, substantially as described.

5. A device of the character described, 95 comprising a hollow plunger constituting a passage for brads, a shell secured around the plunger and spaced therefrom, said shell having a slot therein, a barrel located between the shell and the plunger, a spring exerting downward pressure on the barrel, 100 a pivoted lever, a bar, said shell and plunger having openings for the reception of the bar, said barrel having a slot for the reception of said bar, said lever connected at its free end to said bar, a spring exerting inward pressure on the lever, a wedge block fixed to the barrel and projecting through the slot in the shell and engaging said lever, the lower end of said barrel having a restricted 105 spring mouth through which said brads are driven, and a cushion secured to the lower end of said barrel, substantially as described.

6. A device of the character described, 115 comprising a hollow plunger constituting a passage for brads, a shell secured around the plunger and spaced therefrom, said shell having a slot therein, a barrel located between the shell and the plunger, a spring exerting downward pressure on the barrel, 120 a pivoted lever, a bar, said shell and plunger having openings for the reception of the bar, said barrel having a slot for the reception of said bar, said lever connected at its free end to said bar, a spring exerting inward pressure on the lever, a wedge block fixed to the barrel and projecting through the slot in the shell and engaging said lever, a handle on the upper end of said plunger, 125 and a reservoir secured in said handle and con- 130

structed to direct brads into the passage of
said plunger, the lower end of said barrel
having a restricted spring mouth through
which said brads are driven, and a cushion
secured to the lower end of said barrel, sub-
stantially as described.

In testimony whereof I have signed my

name to this specification in the presence of
two subscribing witnesses.

ROBERT J. MORRISON.
